UNITED STATES PATENT OFFICE.

WILLIAM H. SAUVAGE, OF NEW YORK, N. Y., ASSIGNOR TO SAUVAGE-WARD BRAKE COMPANY, INC., A CORPORATION OF DELAWARE.

SLACK-ADJUSTER FOR RAILWAY-BRAKES.

1,117,707.

Specification of Letters Patent. Patented Nov. 17, 1914.

Application filed March 7, 1913. Serial No. 752,591.

To all whom it may concern:

Be it known that I, WILLIAM H. SAUVAGE, a citizen of the United States, residing in the borough of Manhattan of the city of New York, in the county of New York, in the State of New York, have invented certain new and useful Improvements in Slack-Adjusters for Railway-Brakes, of which the following is a specification, reference being had to the accompanying drawings, which form a part hereof.

This invention relates to automatic slack adjusters designed primarily with reference to their use on cars of the maximum traction truck type, but equally applicable, by suitable modifications to be indicated, to cars employing trucks of the usual standard types. The invention is concerned more particularly with such devices, commonly known in the art as shim slack adjusters.

It has for an object to improve generally the construction and arrangement of such adjusters whereby the efficiency thereof is increased and the operation, in the manner intended, insured under all conditions of use.

In the embodiment herein illustrated the shim slack adjuster is shown, as usual, in combination with an adjusting rod, the function of which is well known in the art, but the construction and arrangement of which are generally improved in this invention.

In accordance with the present invention, in so far as its application to a maximum traction truck is concerned, the equivalents of the usual dead levers are provided by short brake arms pivotally supported on beams secured to the car body or any available stationary support. It is to these short brake arms that the brake shoes of the smaller wheels of the truck, are secured. The brake shoes controlling the driving wheels may be suspended in the ordinary manner. The action of the brakes is controlled through a live lever. It is to provide devices operable automatically in case of excess travel of this live lever, due to wear of the movable parts of the brake system, and to compensate for such wear, that this invention is made.

It is further sought to dispose the operating parts of such devices in protected positions so that they will not be subject to the ravages of the elements.

Still another aim is to regulate the adjusting members so that the slack taken up with respect to each pair of brake shoes shall be proportional substantially to the amount of wear to which such shoes are subjected. 60

As indicated above, the invention may be applied also to standard trucks and the general objects above set forth are sought to be realized when the invention is embodied in the brake equipment of trucks of the last 65 named type.

Further improvements in the present invention will appear expressly as this description proceeds, and other inherent advantages resulting from the structure employed will be apparent to those skilled in the art. 70

The invention will be now described in detail with reference to the accompanying drawings in which— 75

Figure 1 is a view partly in side elevation and partly in section of a maximum traction truck equipped with a slack adjuster constructed in accordance with the present invention. Fig. 2 is a view in plan of the 80 truck shown in Fig. 1. Fig. 3 is a fragmentary view in elevation on an enlarged scale showing the relation of the live lever to the brake beams. Fig. 4 is a detail view on an enlarged scale showing the relation of the 85 improved slack adjuster and adjusting rod to the live lever and the brake beams. Fig. 5 is a detail view, partly in section of an improved clutch employed in connection with the adjusting rod and with all of the 90 parts shown reversed from the arrangement illustrated in Fig. 4. Fig. 6 is a view in end elevation of one of the clutch members shown in Fig. 5. Fig. 7 is a view taken on the plane indicated by the line 7—7 in Fig. 5 and looking in the direction of the arrows. Fig. 8 is a view similar to Fig. 1 showing the application of a slack adjuster constructed in accordance with the present invention to a standard truck. Fig. 9 is a 100 view in plan of the truck shown in Fig. 8.

In the embodiment herein illustrated a rigid frame member *a* mounted on bolsters *b* and *c* of the wheels *b'* and *c'* respectively, has connected thereto transoms *d* from 105 which are suspended pivotally hangers *e*, carrying brake shoes *e'* of the usual type and adapted to be applied to the driving wheels *c'*. These hangers *e* may be rigidly connected by and support, as is usual, a 110

transverse brake beam e^2 adapted to swing therewith. On a transverse beam f secured to any stationary supporting frame are pivotally mounted brake arms g carrying brake shoes g' which are applied to the smaller wheels b' of the truck. The brake arms g have secured thereto between their points of suspension to the supporting beam f and the point of attachment to the brake shoes g' , controlling rods g^2 which are bolted to the ends of a second transverse beam g^3 , which is movably disposed under the above described brake beam e^2 . Substantially midway between the ends of the swinging beam 15 g^3 is adjustably secured thereto, a rod h which is operatively connected to the live lever i , the latter being operatively connected to the usual source of power.

An adjustable connection between the beam g^3 and the threaded rod h is shown clearly in Fig. 4. As it appears from this figure, the beam g^3 is provided with a tubular bracket g^4 , on either side of which are disposed nuts h' and h^2 threaded on the rod 20 h and movable manually thereon to determine the position of said rod with respect to the beam g^3 , for a purpose which will hereafter appear.

The swinging brake beam e^2 carries a bracket e^3 on which is formed a stud e^4 . On this stud is supported one end of the improved shim slack adjuster, which will now be described. The frame of this adjuster comprises an integral casting k having formed therethrough a vertical slot in which is disposed movably the live lever i . In the side faces of the casting k are formed longitudinal slots k' in which is disposed a pin i' passing through the live lever i and serving as a support for the slack adjuster. Adjacent to the outer end of the casting k is formed a chamber k^2 for shims l , the purpose of which will appear later. This chamber k^2 has a removable bottom k^3 by which 45 the shims may be inserted or removed as desired. In the bottom is formed a longitudinal slot to receive the flanged portions of the shims when the latter are permitted to drop from their upper position to a lower position. Extending into the chamber k^2 and longitudinally thereof is a push rod m which 50 is operatively connected to the live lever i by the pivot pin i' . The length of that portion of the push rod m which lies normally within the chamber k^2 is equal substantially to the length of said chamber, so that most of the shims l when in their upper position rest on the push rod and are supported thereby. When the push rod m is withdrawn partially from the chamber k^2 one or more of the shims l will be permitted to drop to the lower position, depending upon the extent of movement of the push rod and the thickness of each shim. By the arrangement described a solid abutment is always

found between the inner end of the push rod and the end wall of the shim chamber k^2 . The operation of the parts just described with relation to the slack in the brake system will be pointed out more fully hereinafter. 70

The pin e^4 , which is carried in the bracket e^3 , as described, supports a clutch member n which has formed therein a slot n' to permit relative movement between said pin and the clutch member. In accordance with this invention the clutch member n is formed at one end with a depending collar n^2 which receives an adjusting rod o , and at its other end with an interiorly tapered yoke n^3 within which said adjusting rod is likewise disposed. The yoke n^3 has disposed snugly therein a correspondingly tapered wedge p which co-operates with the inner face of the yoke n^3 and which embraces partially said adjusting rod. The wedge p is forced outwardly with respect to the clutch n by means of a spiral spring q which encircles the adjusting rod o and lies between the collar n^2 and the inner end of the wedge. By reason of the interposition of the wedge between the adjusting rod o and the tapered inner face of the yoke n^3 , a wedging action is brought about when the adjusting rod and the wedge are moved to the right with respect to the clutch, the rod being then forced into the narrower lower part of the yoke and gripped thereby. However, free movement of the rod through the yoke and the collar is permitted in the opposite direction. In accomplishing the desired compensating effect herein, it is necessary that during the movement of the rod o to the right (Fig. 4) the swinging beam g^3 , which controls the movement of the brakes g' of the smaller wheels b' , should be connected with the brakes e' which co-operate with the tread of the driving wheels c' . This connection is made through the adjusting rod o , which has a depending loop o' on one end, through which extends the threaded rod h . In the interests of simplicity and rigidity, the depending loop o' is disposed between the swinging beam g^3 and one of the nuts h' , by which the relation of the beam and the operating rod h , may be varied. 100

Although the general construction of the several parts of the brake system has been described and their respective functions indicated, it is believed that a detailed recital of their operation will afford a clearer understanding of the present invention. When the brakes are to be adjusted initially and given any desired clearance, such adjustment may be obtained partially through the manual operation of the nuts h' and h^2 . By these manual devices the relative position of the brakes g' of the smaller wheels b' and the live lever i may be determined. The shims l in the shim box k^2 may be 110

moved to their upper position so as to permit the push rod m to be moved into the chamber and the pin i' assume a position adjacent the inner end of the slots k' in the sides of the shim frame k . The clutch n , after the desired clearance of the larger brake shoes e is obtained, may be slid along the adjusting rod o until the pin e^4 is disposed in the right hand end of the slot n' as seen in Fig. 4. In Fig. 5 the pin is shown in the other end of the slot, this figure showing all of the parts reversed with respect to the arrangement shown in Fig. 4. When the parts are all placed as indicated above, it will be understood that the inner end of the push rod m abuts against either the end wall of the shim box k^2 or against one of the shims l , and that accordingly movement of the live lever in the direction indicated by the arrow in Fig. 1, will, through the pin e^4 and the beam e^2 , apply the brakes e' . Practically simultaneously, the brakes g' will be applied, through the rod h , the swinging beam g^3 , rods g^2 and brake arms g . By reason of the slot n' the relative movement of the pin e^4 with respect to the clutch n , which ensues during the application described, is permitted. The length of the slot n' is such as to permit travel of the brakes through their normal clearance space only, and excess travel of the brakes will result in the engagement of the pin e^4 with the clutch n at the left hand end of the slot n' . After such engagement, further movement of the brakes will cause the clutch n to slide on the adjusting rod o , a distance equal to the excess travel. When the brakes are released, the stud e^4 will move to the right hand end of the slot n' , as seen in Fig. 4, but further relative movement is prevented by the gripping of the rod o by the yoke n^2 through the wedging action of the wedge p in the yoke. Continued movement of the live lever i to its normal position, which may be effected by a suitable coil spring i^2 operatively disposed with respect to the lever, will result in movement of the pin i' in the slots k' of the shim frame. Such movement of the pin i' will result in the partial withdrawal of the push rod m from the shim box k^2 , thus permitting one or more of the shims l to drop to the lower position and form a solid abutment between the end of the push rod and the end wall of the shim box, as indicated more clearly in Fig. 4. It will now be clear that the primary function of the adjusting rod o is to maintain the brakes g' and e' in their normal clearance position regardless of slack in the brake rigging or wear of any of the parts. It will be equally clear that the function of the shim slack adjuster is to compensate automatically for such wear so that movement of the live lever from its normal position will result invariably in the application of the brakes, with the same power

and during the same period of travel of the live lever.

Before pointing out more in detail the advantages incidental to the use of a system embodying the present improvements, the application of such a system to the standard truck shown in Figs. 8 and 9 will be described, since all such advantages are common to all conditions of use. In these figures corresponding reference characters indicate parts corresponding to those described in Fig. 1 and it is deemed unnecessary to here set forth a detailed description of these parts, except in so far as they are modified. In this type of truck, as is usual, a dead lever r is suspended from a bracket s , secured fixedly to any convenient portion of the car body, and provided with a series of apertures to receive the pivot pin of the dead lever for the purpose of permitting initial adjustment of the fulcrum of the latter. The brakes g' in this embodiment, which are applied to the wheels b^2 , corresponding to the smaller wheels b' in the maximum traction truck, are carried by hangers g^3 pivoted to the ear truck, as will be understood. The lower ends of the live lever i and the dead lever r are connected rigidly by a bottom bar t having a plurality of apertures t' therein to permit the relative adjustment of the lower ends of said levers. It will now be clear that movement of the live lever i in the direction indicated by the arrow in Fig. 8 will bring about the application of the brakes e' and g' in the ordinary manner, and as pointed out in detail hereinbefore. In the modification, now under discussion, the shim frame k is carried directly by the swinging brake beam e^2 , and the operation of the slack adjuster is in no way different from that pointed out with reference to its use on a maximum traction truck. However, the arrangement of the adjusting rod designated o^2 is changed to meet the requirements of slightly modified use. As shown in Fig. 8, one end of the adjusting rod o^2 has secured to it a bracket o^3 which is pivotally connected to the dead lever r , at a point intermediate its ends, which point may conveniently be coincident with the point of attachment of this lever to its brake beam g^3 . The other end of the rod o^2 extends freely through a clutch, herein designated generally by the reference character n^4 , which may be of the same construction as the clutch shown in Fig. 4. The yoke or outer clutch member is suspended directly on the shim frame k by a pin e^5 and normal travel of the brakes, without operation of the adjusting devices, is secured through a slot n^5 in which said pin may move, all as explained with respect to the embodiment previously described.

The advantages resulting from the employment of the novel features of construc-

tion herein described and the improved arrangement of parts, as pointed out, will appear to one skilled in the art. However, it may be conducive to a clearer understanding of these advantages to set them forth briefly.

In previous constructions where a shim box and shims have been employed the automatic adjusting devices have been mounted in the lowermost parts of the brake rigging so that the devices were subjected to damage by mud, snow, etc. In the present construction, the slack adjuster has been disposed at the highest point possible to insure an efficient operation thereof, and it has been constructed with a view to inclosing, as much as possible, all of the moving parts. For instance, it will be evident that foreign particles may not enter the shim chamber readily, since the open portions thereof are always closed completely by either the shims or the moving push rod.

Another feature of the invention which should be emphasized here is the improved clutch illustrated particularly in Fig. 4-7. This clutch, while highly effective and certain in its operation, prevents relative movement of the push rod with it, by a comparatively yielding grip. It is specially desirable to have a yielding clutch at this point in the brake rigging since a sudden application of the brakes together with an excess travel thereof, ordinarily imposes severe strains and often results in the fracture of the adjusting rod. As pointed out in connection with the description of this clutch, free movement between the clutch and the adjusting rod in one direction is permitted.

Other modifications of this structure will suggest themselves to skilled mechanics but all such changes in form are to be deemed within the scope of this invention provided the advantages herein sought to be realized, result by the employment of any features of construction set forth in the appended claims.

I claim as my invention:

1. In a brake system, the combination of brake shoes, a live-lever to control the movement thereof, slack adjusting means supported by the brake rigging and including a frame disposed intermediate the ends of the live lever and having slots therein, a fulcrum pin for the live lever carried intermediate the ends thereof and movably mounted in said slots, a slide secured to said pivot pin and adapted to engage operatively a portion of said frame to move the brakes, and shims mounted in the frame and arranged to shift successively to fill the space between the end of the slide and the frame as the slack is taken up.
2. In a brake system, brake shoes to contact with adjacent wheels, and means operatively connecting said shoes, said means including a clutch composed of a slotted

sleeve having a slot and stud connection with one set of brake shoes, a rod connected to the other set of brake shoes and disposed longitudinally in the slotted sleeve, the inner wall of the sleeve being tapered, a correspondingly tapered wedge member disposed between the rod and the tapered wall of the sleeve and operative to permit free relative movement of the sleeve and rod in one direction while insuring a yielding engagement thereof to limit their relative movement in the opposite direction.

3. In combination with a traction truck having driving wheels and idle wheel, a swinging brake beam secured to the brake shoes of the driving wheels, a second swinging beam lying under the brake beam, a live lever, an adjustable connection between the second named beam and the live lever, rods secured to the second named beam adjacent its extremities and secured operatively to the brake beam of the idle wheels, and an operative connection between said last named beam and the brake beam, said connection including a clutch permitting free relative movement of the beams in one direction and insuring a yielding engagement therebetween to limit their relative movement in the opposite direction.

4. In combination with a traction truck having driving wheels and idle wheels, a swinging brake beam secured to the brake shoes of the driving wheels, a second swinging beam lying under the brake beam, a live lever, an adjustable connection between the second named beam and the live lever, rods secured to the second named beam adjacent its extremities and secured operatively to the brake beam of the idle wheels, an operative connection between said last named beam and the brake beam, said connection including a clutch permitting free relative movement of the beams in one direction and insuring a yielding engagement therebetween to limit their relative movement in the opposite direction, and independent means operatively connected to the live lever and to the brake beam to take up the slack.

5. In combination with a traction truck having driving wheels and idle wheels, a swinging brake beam secured to the brake shoes of the driving wheels, a second swinging beam lying under the brake beam, a live lever, an adjustable connection between the second named beam and the live lever, rods secured to the second named beam adjacent its extremities and secured operatively to the brake beam of the idle wheels, an operative connection between said last named beam and the brake beam, said connection including a clutch permitting free relative movement of the beam in one direction and insuring a yielding engagement therebetween to limit their relative move-

- ment in the opposite direction, and independent means supported on the brake beam and on the live lever intermediate the ends of the latter to take up the slack in the brake rigging.
6. In combination with a traction truck having driving wheels and idle wheels, a swinging brake beam secured to the brake shoes of the driving wheels, a second swinging beam lying under the brake beam, a live lever, an adjustable connection between the second named beam and the live lever, rods secured to the second named beam adjacent its extremities and secured operatively to the brake shoes of the idle wheels, an operative connection between said last named beam and the brake beam, said connection including a clutch permitting free relative movement of the beam in one direction and insuring a yielding engagement therebetween to limit their relative movement in the opposite direction, and independent means coöperating with said last named connection to take up the slack in the brake rigging, said means including a movable fulcrum for the live lever and means operable automatically to maintain the fulcrum in its adjusted position in accordance with the excess travel of the live lever.
7. In combination with a truck having driving wheels and idle wheels, brake shoes coöperating with the driving wheels, a brake beam secured to said shoes, beamless brake shoes coöperating with the idle wheels, means to connect operatively the two sets of brake shoes and automatic slack adjuster devices to take up slack disposed operatively in that portion of the brake rigging which is carried by the truck.
8. In combination with a truck having driving wheels and idle wheels, brake shoes coöperating with the driving wheels, a brake beam secured to said shoes, beamless brake shoes coöperating with the idle wheels, means to connect operatively the two sets of brake shoes and an automatic slack adjuster device part of which is disposed in said connection.
- 50 9. The combination of a truck having driving wheels and idle wheels, brake shoes coöperating with the driving wheels, beamless brake shoes coöperating with the idle wheels, means to connect operatively the two sets of brake shoes, a live lever to control the movement of the brake shoes, a beamless brake beam secured to said shoes, beamless brake shoes coöperating with the idle wheels, a shim box mounted in the brake rigging, a series of shims disposed within said shim box, and means operatively disposed between the shims and the live lever whereby upon excess travel of the live lever the shims may shift successively to take up automatically the slack in the rigging.
10. In combination with a truck having driving wheels and idle wheels, brake shoes coöperating with the driving wheels, beamless brake shoes coöperating with the idle wheels, a live lever to control the movement of the brake shoes, a slack take-up device disposed in said last named connection and operative automatically upon excess travel of the live lever to take up the slack in the rigging.
11. In combination with a truck having driving wheels and idle wheels, brake shoes coöperating with the driving wheels, a brake beam secured to said shoes, beamless brake shoes coöperating with the idle wheels, a shim box mounted in the brake rigging, a series of shims disposed within said shim box, and means operatively disposed between the shims and the live lever whereby upon excess travel of the live lever the shims may shift successively to take up automatically the slack in the rigging.
12. In combination with a truck having driving wheels and idle wheels, brake shoes coöperating with the driving wheels, a brake beam secured to said shoes, beamless brake shoes coöperating with the idle wheels, a live lever to control the movement of the shoes, a connection between the live lever and the beamless brake shoes, a shim box mounted on the live lever, a series of shims disposed within said box, a push rod mounted on the live lever and coöperating with said shims whereby upon excess travel of the live lever the shims are permitted to shift successively to take up automatically the slack in the rigging.

This specification signed and witnessed 100
this 28th day of February, A. D. 1913.
